UNITED STATES PATENT OFFICE.

WILHELM SCHLOEMILCH, OF BERLIN, GERMANY, ASSIGNOR TO GESELLSCHAFT FÜR DRAHTLOSE TELEGRAPHIE M. B. H., OF BERLIN, GERMANY, A CORPORATION OF GERMANY.

SOUND-REPRODUCING ARRANGEMENT.

Application filed October 23, 1923. Serial No. 670,223.

To all whom it may concern:

Be it known that I, WILHELM SCHLOEMILCH, a citizen of Germany, and a resident of Hallesches Ufer 12/13, Berlin, S. W. 11, Germany, have invented new and useful Improvements in Sound-Reproducing Arrangements, of which the following is a specification, accompanied by drawings.

- 10 The invention relates to a loud speaker which differs from those heretofore known in so far as instead of a membrane, an elastic body which has no natural vibration is employed.
- 15 Many attempts have been made to use the electro-mechanical movements produced by speech-current for controlling the velocity of an issuing gas-current or vapour-current by valves or the like and for producing 20 loud speech in this way. All these former attempts failed, because it was not possible to construct the proposed valves or throttle-valves of such a small mass as to enable them to follow the very quick oscillations 25 corresponding to the highest harmonics.

Another disadvantage of all these arrangements was that the current of air passing hard and sharp edges or curves produced a whistling sound and that the graduation 30 of sound became too coarse and hard.

In contrast with these devices, the present invention imitates the mechanism of the human larynx to a certain degree. The exhaust of a current of air is controlled by altering the diameter of a flexible air conduit made of caoutchouc or other similar soft material in a mechanical or electro-magnetic way by means of mechanical movements in the rhythm of speech. When a constant 35 current of air is simultaneously sent through the conduit, we obtain by very simple means a loud reproduction of human speech of good timbre.

It is preferable to imitate the mechanism 40 of the human organs of speech also in so far as to provide at the exhaust end of the flexible air conduit, a chamber which is half or less open and resonant to the means frequency of the sound.

45 The invention is schematically represented in the accompanying drawing.

The terminals of the winding of an electromagnet having a core M and armature S are denoted by a and b. L denotes a pipe

leading from the source of air (not shown). 55 The pipe L leads into the air chamber W. Leading from the air chamber W is a flexible air conduit O which leads to the resonating chamber R corresponding to the human oral cavity. Leading out of the chamber R is the horn T for delivering the sound.

It will be noted that the flexible conduit O passes between the stationary and adjustable anchor member S¹ and the armature S. The walls of the flexible conduit O are pressed and slightly flattened between said anchor member S¹ and armature S as shown in the drawing. When an electric current in the form of sound variations is impressed 65 upon the terminals a, b of the winding of the electromagnet, armature S will be caused to vibrate according to said sound variations. The vibrations of the armature S will cause the walls of the flexible conduit O to flex 70 and the cross sectional area of the conduit O is thereby varied according to the electric sound variations.

The variations in cross-sectional area of the conduit O will cause the air flowing 75 through the conduit to vary. These variations will be resonated in chamber R and will be delivered through the horn T.

It is possible to form an acoustic amplifier-cascade in a suitable way with several 80 of such apparatuses by using the alteration of one arrangement for controlling the next.

Having described my invention, what I 85 claim is:

1. A sound reproducing arrangement comprising a flexible gas conduit and means for electromagnetically altering the cross-sectional area of the conduit in accordance with sound waves.

2. An acoustic arrangement comprising, a flexible gas conduit, a device engaging and flattening said conduit at a point along its length, and means for controlling said device whereby the wall of said conduit is caused 90 to flex in accordance with sound variations.

3. A sound reproducing arrangement comprising a flexible gas conduit, a device arranged to flatten the conduit at a point along its length, and means for operating 95 said device in accordance with sound waves to vary the cross-sectional area of the conduit at said point.

4. A sound reproducing arrangement comprising a flexible gas conduit, a controlling device arranged to flatten the conduit at a point along its length, and means for electromagnetically operating said device in accordance with sound waves.
5. A sound reproducing arrangement comprising a flexible gas conduit, a controlling device arranged to flatten the gas conduit at a point along its length, means for electromagnetically operating said device in accordance with sound waves, and a chamber on the exhaust side of said conduit which is resonant to the mean frequency of the sound waves.
- 10 6. A sound reproducing arrangement comprising gas chamber, a flexible gas conduit connected with the outlet of said chamber,

a controlling device arranged to flatten the gas conduit at a point along its length, 20 means for electromagnetically operating said device in accordance with sound waves, and a chamber on the exhaust side of said conduit which is resonant to the mean frequency of the sound waves.

25 7. An acoustic arrangement comprising, a flexible gas conduit, an anchor member engaging said conduit at a point along its length, an electromagnet having a winding and armature, said armature engaging said conduit on the opposite side thereof from said member, said conduit being pressed between said armature and said member and its walls flexing in accordance with electric sound waves impressed on said winding.

WILHELM SCHLOEMILCH.
